UNITED STATES PATENT OFFICE.

JOSEPH PERRA, OF PHILADELPHIA, PENNSYLVANIA.

EXCAVATOR AND PILE DRIVER.

1,411,180.

Specification of Letters Patent. Patented Mar. 28, 1922.

Application filed July 18, 1919. Serial No. 311,782.

To all whom it may concern.

Be it known that I, JOSEPH PERRA, a citizen of the United States, residing at Philadelphia, in the county of Philadelphia and State of Pennsylvania, have invented new and useful Improvements in Excavators and Pile Drivers, of which the following is a specification.

My invention relates to new and useful improvements in combination excavators and pile drivers, and has for its object to provide in combination with an excavator of peculiar and unique construction, a pile driver which may be moved from one point 10 to another along the excavator frame to place it in the proper position if driving piles ordinarily termed shoring boards.

A further object of the invention is to provide an excavator frame provided with certain tracks on which run suitable trucks carrying a guide for a pneumatic hammer or driver which is adapted to follow the shoring as the same is to be driven into place, the raising and lowering of the hammer and the movements of the trucks being controlled by a suitable source of power such as engine.

A further object of the invention is to provide an adjustable frame for an excavator which may be adjusted before being set up to accommodate the width of the trench and the height of which may be regulated according to the height of over head structures in the locality where the work is being done.

A still further object of the invention is to provide an improved trolley having improved means for holding the bucket hanger with the bucket in a raised position.

Another object of the invention is to provide a locking support adapted to be pivoted to the trolley of an excavator which will be actuated by the shaft in a bucket hanger to permit the said shaft to pass the locking support, the latter then being returned to its normal position by gravity or with the assistance of a spring so that the bucket hanger with the bucket thereon will be supported to relieve the hoisting ropes or cables and at the same time prevent the bucket from descending until desired.

With these ends in view my invention consists in the details of construction and combination of elements hereinafter set forth and then specifically designated by the claim.

In order that those skilled in the art to which this invention appertains may understand how to make and use the same, I will describe its construction in detail referring by numerals to the accompanying drawings forming a part of this application in which:

Fig. 1, is a fragmentary side elevation of an excavator frame showing my improved pile driver combined therewith.

Fig. 2, is a vertical sectional view thereof.

Fig. 3, is a plan view of a portion of the excavator frame showing the manner in which it may be constructed to permit the passage of the pile driver from one side to another.

Fig. 4, is an end or edge view of my improved excavator trolley having a locking support thereon and showing the relation of the parts to a supporting track, and

Fig. 5, is a longitudinal vertical section thereof, a portion of the track being broken away to clearly illustrate the construction.

In carrying out my invention as here embodied 2 represents a trench which is being excavated for the laying of a sewer, pipes or other underground objects, the side walls of the trench being held in position or pressed by suitable shoring boards 3.

Along the course of the trench to be excavated are placed a number of ties or sleepers 4 to which are fastened in any suitable manner the runners or joists 5 which carry the rails 6 of the track for the excavating frame.

If found desirable the runners 5 may be eliminated and the tracks placed directly upon the ties.

The conveyor frame consists of a number of uprights 7, arranged in pairs preferably converging toward their upper ends, each of the uprights of a coacting pair have crossed bars 8 and 9 secured thereto, the former being near the lower ends and the latter near the upper ends of the uprights. These cross bars having a number of holes 10 whereby the cross bars of one upright may be fastened to the cross bars of the coacting upright by means of bolts or their equivalent 11.

The lower ends of each of the coacting pair of uprights are suitably mounted on axles 12, on the outer ends of which are journaled flange wheels 13 for running upon the rails 6.

The upper ends of the supports 7 are provided with projections 14 above the upper

cross bars 9 and to these projections are adjustably secured the extension members 15 held in their desired adjustments by bolts 16 or their equivalent passing through the projections of the uprights and through holes 17 in the extension members. These extension members carry reach members 18 the inner ends of coacting pairs overlapping and held in position or their desired adjustment by bolts 19 or their equivalent passing through holes 20 in the overlapping ends.

To the reach members 18 is secured the pile driver supporting track 21, which track if found desirable is fastened or bent to form a curve 22 at one end of the excavator frame so that where a single pile driver is used the same may be moved about to either side. The track 21 is preferably formed from I beam and has mounted thereon a truck 23 which consists of a suitable frame 24 and wheels 25 for running on the lower flanges of the track 21.

On the supports or uprights 7 adjacent their lower ends are mounted guide tracks 26 in which runs a wheel 27 carried by the lower end of the guide 28. On this guide is slidably mounted a pneumatic hammer or pile driver 29, the same being raised and lowered by means of a cable 30 wound about the drum 31 and running over a sheave 32 located in some suitable position on the excavator frame then over a sheave 33 carried by the truck, then about the sheave 34 of the hanger 35 and then over the inner sheave 36 carried by the truck, the opposite end being permanently fastened at some suitable point as to the excavator frame.

The truck 23 is moved along its track in any desirable well known manner, one way of so moving the truck is here shown which consists of attaching a cable 37 thereto and winding said cable upon a drum 38. The different drums for actuating the different parts of the mechanism are revolved in any well known manner and by any suitable power as by steam, electricity or by compressed air.

The pile driver or pneumatic hammer 29 consists of a casing 39 provided with guide lugs 40 for engagement with the guide 28 and the hammer 41 is actuated by compressed air, steam or other suitable operating fluid conveyed to the casing through a suitable pipe 42 from a suitable source. The pneumatic hammer or pile driver may be constructed in any of the well known forms, wherein the portions of a suitable element will produce a sufficient blow to be transmitted through the hammer to the shoring board or pile for driving the same into the ground.

To the cross bars 9 is secured a trolley supporting track 43 preferably in the form of an I beam on which runs the trolley 44. The trolley consists of two spaced side plates 45 rigidly held in position by suitable rods or

bolts 46, some of which act as axles for the different sheaves 47 and 48 and over these sheaves runs a hoisting cable 49 from a suitable hoisting apparatus, one of the drums of which as 50 may be utilized for winding up said hoisting cable. This cable also passes about a sheave 51 carried by the bucket hanger 52 and the shaft or axle 53 of said bucket hanger on which the sheave 51 is journaled, has its ends projecting beyond the sides of the bucket hanger as plainly shown in Fig. 4 and in order that said bucket hanger may pass into the trolley with the shaft 53 above the lower edge of the side plates of the trolley, I form slots 54 in each of the side plates 45 open at their lower ends and having their side edges converging toward their upper ends to act as guides for properly positioning the bucket hanger.

Between the side plates of the trolley is mounted a locking support 55 comprising two parallel members 56 mounted upon a rod 57, the ends of which are mounted in the side plates and the inner ends of these members 56 projecting across the slots 54 and each member has a notch 58 in its upper edge at the inner end for registration with the shaft or axle 53. In the outer ends of the members 56 is mounted a stop rod 59, the ends of which project beyond the side plates of the trolley and are adapted to engage the lower edge of said plates to limit the movement of the locking support in one direction and the fulcrum of said locking support is so positioned that the inner end thereof will overbalance the outer end and normally take the position shown in Fig. 5, but in order to guard against the possibility of the locking support not returning to its normal position after operation, a spring 60 may be utilized for positively returning said locking support to its normal position.

The locking support may be manually actuated by a pull rope 61 fastened to its outer end or by another pull rope 62 attached to some suitable portion of its inner end and running over a sheave 63 between the side plates of the trolley and then over a sheave 64 carried by a sheave trolley 65 provided with wheels 66 for running on the track 43 and said sheave trolley is spaced some distance from one end of the trolley 44 but connected to the latter so as to move therewith by means of a coupling bar 67. The locking support may also be actuated from the other end of the trolley by means of a pull rope 68 running over another sheave 64 carried by another sheave trolley 65 having wheels 66 and also over another sheave 69 or groove pulley 69 located between the side plates of the trolley 44, the sheave trolley 65 latterly referred to being also connected with the trolley 44, but at the other end thereto by means of a coupling bar 67.

When the bucket is to be drawn out and transported from one position to another along the excavator frame, said bucket is hoisted until the ends of the shaft or axle 53 pass into the slots 54 in the side plates of the trolley 44 where said ends of the shaft or axle 53 will engage the end sides or edges of the members 56 at the inner end of the locking support, thereby moving said 10 inner end of the locking support about its fulcrum to permit the passage of the shaft or axle 53 beyond the inner end of the locking support at which time said axle will be disengaged from the inner end of the 15 locking support and said locking support will return to its normal position until stopped by the contact of the projecting ends of the stop rod 59 with the lower edges of the side plates of the trolley. By releasing 20 the hoisting cable 49, the bucket and its hanger will then descend until the ends of the shaft or axle 53 rest in the notches 58 in the inner ends of the members 56 at which time the locking support will support the 25 entire weight of the bucket and relieve the strain upon the hoisting cable.

After the bucket has been transported to the point desired, the bucket is again hoisted the necessary distance which will permit the 30 inner ends of the members 56 to pass the shaft or axle 53 at which time said locking support may be moved from the path of travel of the shaft or axle 53 in its downward course by pulling upon any one of 35 the pull ropes 61, 62, or 68 and as two of these pull ropes are located some distance from the trolley itself, the bucket may be released by a person some distance from the same, thus overcoming to a great extent the 40 possibility of injury or loss of life.

During the excavation of the trench along one portion of the operation, shoring boards or piles may be driven by mechanical means supported by the same framework which 45 carries the bucket trolley. To do this work the shoring boards are set in position as shown in Fig. 1 and the pile driver 29 then moved to the proper position by running this supporting truck 23 along the track 21 and 50 then releasing its hoisting rope or cable so that the hammer rests upon the end of the shoring board to be driven into the ground, after which the operating fluid is turned on and the pile driver permitted to follow up the shoring board as it gradually enters the ground, after the shoring board has been driven home the pile driver is raised and moved to the position of the next shoring board to be placed in position.

Where it's necessary to do the work very 60 quickly and where the digging of the trench can be expedited to keep up with the work of placing the shoring boards two pile drivers may be utilized, one on each side of the excavator frame, but where the trench 65 digging is relatively slow and one pile driver can drive the shoring boards into place with sufficient speed to keep up with the trench work, a single pile driver may be utilized on both sides of the excavator frame by 70 moving it around the curve 22 at one end of the excavator frame.

Of course I do not wish to be limited to the exact details of construction as herein shown as these may be varied within the 75 limits of the appended claim without departing from the spirit of my invention.

Having thus fully described my invention what I claim as new and patentable is:—

In a device of the character stated a trolley 80 consisting of two side plates having slots therein at the lower edges thereof, the side edges of said slots converging inwardly or toward their upper ends, rods for securing the side plates in position and holding them 85 apart, wheels for supporting said trolley upon a track, a locking support consisting of two parallel members fulcrumed between the side plates with their inner ends projecting across the slots in said side plates, said inner 90 ends of said members having notches therein, a stop rod carried by the outer ends of said members, the ends of said rods projecting beyond the side plates and adapted to engage the edges thereof to limit the movement of the locking support in one direction, means for normally forcing said locking support to its normal position, sheaves journaled between the side plates of the trolley, 95 a hoisting cable running thereover, a bucket 100 hanger, a shaft or axle therein having projecting ends for registration with the slots in the side plates of the trolley and for engagement with the inner end of the locking support, when the bucket hanger is raised, 105 a sheave on said shaft or axle about which the hoisting cable runs for supporting the bucket hanger, sheave trolleys each carrying a sheave, wheels also carried by said trolleys for moving the same upon a track, coupling 110 bars for connecting said sheave trolley with the bucket trolley and pull ropes for manually operating the locking support, certain of said pull ropes passing over the sheaves carried by the sheave trolleys. 115

In testimony whereof, I have hereunto affixed my signature.

JOSEPH PERRA.
